UNITED STATES PATENT OFFICE.

ROUGHSEdge WALLWORK AND ARTHUR C. WELLS, OF MANCHESTER,
COUNTY OF LANCASTER, ENGLAND.

REGENERATIVE BURNER.

SPECIFICATION forming part of Letters Patent No. 404,063, dated May 28, 1889.

Application filed September 14, 1888. Serial No. 285,382. (No model.) Patented in Belgium April 24, 1888, No. 81,537.

To all whom it may concern:

Be it known that we, ROUGHSEdge WALLWORK and ARTHUR C. WELLS, subjects of the Queen of England, residing at Manchester, in the county of Lancaster, England, have invented certain new and useful Improvements in Regenerative Burners, (for which we have obtained Letters Patent in Belgium, dated April 24, 1888, No. 81,537;) and we do hereby declare the following to be a full, clear, and exact description of the invention, such as will enable others skilled in the art to which it app pertains to make and use the same, reference being had to the accompanying drawings, and to letters or figures of reference marked thereon, which form a part of this specification.

In the drawings, Figure 1 is an elevation of our improved regenerative burner supplied with combustible liquid from a stationary or portable reservoir, and Fig. 1^a is a detail view. Fig. 2 is a sectional elevation of the burner and its connection with the supply-pipe. Fig. 3 is a top plan view of the burner, the shield being removed and shown in dotted lines. Fig. 4 is an end view of the burner, the shield being also shown in dotted lines. Fig. 5 is a top plan view of the burner-shields, and Fig. 6 an end elevation thereof. Fig. 7 is a top plan view of a portion of the burner-shield and its directing-vane. Fig. 8 is a top plan view of a double burner embodying our invention, and Fig. 9 an end elevation thereof. Figs. 10, 11, and 12 are detail sectional views of the injector-nozzle. Fig. 13 is an end elevation of Fig. 12.

This invention relates to that class of burners known as "regenerative" burners, and more especially designed for use with combustible liquids, the liquid being converted into a gas prior to its reaching the zone of combustion.

Our improved burner is intended more particularly to be used in the open atmosphere, where it is subjected to the action of currents of air liable to vary in direction. The burner is also intended for the use of the cheaper impure hydrocarbons or products of hydrocarbons usually combined with more or less tar and other impurities, though it may be employed for burning pure or refined hydro-

carbons, or products of hydrocarbons or other more or less volatile combustible liquids.

These burners are admirably adapted for use on board ships above decks, where they are continuously under the influence of strong drafts or currents of air, and they may be provided with a directing-vane to hold the burner at all times on a line with the air-currents.

The invention consists in the combination, with the supply-pipe, of a horizontally-revoluble regenerative burner, substantially as hereinafter described and claimed.

The invention further consists in the combination, with a horizontally-revoluble regenerative burner, of a directing-vane for holding the burner in the direction of an air-current and causing it to shift its position whenever such current shifts from one direction to another, substantially as hereinafter described and claimed.

The invention further consists in the combination, with the burner and the regenerative tubes or pipes, of a shield to protect the burner against rain or snow, and under some conditions of use to prevent the radiation or dissemination of the heat from the flame and direct said heat to the regenerative tubes or pipes, substantially as hereinafter described and claimed.

The invention further consists in structural features and combinations of parts, substantially as hereinafter described and claimed.

A convenient mode of and means for supplying the burner with combustible liquid is shown in Fig. 1, which we do not desire to claim in this application, as such mode and means will be claimed in separate applications for patent, and need, therefore, not be described in detail here, except in so far as may be necessary to the description of the burner. It will be understood, however, that any other means or devices may be used for supplying the illuminant under pressure to the burner.

Referring to Fig. 1, A is the reservoir for the combustible liquid, provided near its bottom with an exhaust stop-cock, a, and near its top with a pressure-indicator, a². Extending into the reservoir is a pump-barrel, A', the head of which, outside of the reservoir, is provided with a branch, a', for a hose, so that a

combustible liquid and an elastic gas—such as air—may be forced into the reservoir and compressed therein, or so that the air in the empty reservoir may be compressed by the combustible liquid forced into said reservoir for forcing said liquid to the burner.

B is the service or supply pipe, provided with regulating devices for regulating the flow of the combustible liquid, which may be 10 of any desired construction, but preferably of the construction and arrangement shown in Fig. 1, as great advantages are derived therefrom. These devices consist of a coupling, 1, provided with lateral branches 2 and 3, diametrically opposite each other, said coupling having an axial partition, 4, extending across the axial plane of said branches 2 and 3. In the partition 4 is formed a port, 5, provided with a cone-seat for the cone end of the regulating-screw 6, that works in an interiorly-threaded stuffing-box, 7. In the branch 3 is screwed a hollow screw-plug, 8, Fig. 1^a, that is open at one end, which end abuts against the partition 4 around the port therein, said hollow screw-plug being provided with peripheral ports 9 and an end flange, 10, the perforated tubular portion being covered with a filtering medium, 11, such as wire-gauze. By means of this arrangement all impurities 30 or solid matter are prevented from passing to the burner, and by unscrewing the plug 8 the filtering medium, as well as the interior of the plug, may be readily cleaned, while ready access is afforded to the interior of the top casing.

The supply-pipe B projects into the reservoir A to near the bottom thereof, and at its outer end is provided with coupling devices for coupling the burner thereto. These devices (shown in section in Fig. 2) consist of a stuffing-box, b, screw-threaded interiorly and provided with an axial aperture for the passage of the burner-pipe E, which also passes through an exteriorly-screw-threaded packing-gland, b', provided with a handle, b², for screwing it into the stuffing-box to compress the packing therein, the pipe E having a collar, e', seated on the stuffing-box gland to form joint at that point and prevent the pipe 45 from entering farther into the supply-pipe B, as shown in Fig. 2. The pipe E is bent and has the burner screwed thereto, so as to hold the latter in a nearly-horizontal plane.

This burner consists of an injector-casing, 55 C, provided with a lateral arm on which is formed a coupling, c', for the pipe E, and the heater or regenerative extension E' of this pipe, that projects some distance beyond the injector C', and is connected with a tubular 60 cross-coupling, c², to which is also connected the return regenerative pipe E², whose inner end is connected with a branch, c³, of the casing C and in communication with the chamber thereof.

65 As will be seen by an inspection of Fig. 3, the regenerative pipes E' E² are arranged parallel to each other on opposite sides of and

immediately above the nozzle of the injector C', so that the flame issuing from the nozzle or from a combining-cone in front of it, hereinafter referred to, will impinge upon the pipes the full length thereof, or nearly so, the combustible liquid having such a distance to travel over intensely-heated surfaces before it can reach the injector-nozzle, as not only to 75 completely volatilize the liquid, but to superheat the vapor or gas, so that the latter will reach the burner in the very best condition for consumption or combustion, and so that when mixed with a suitable volume of atmospheric air the maximum illuminating or heating power is obtained from a given illuminant. The pipes as arranged form substantially a multitubular converter or regenerator heated by the burner-flame.

The cross-coupling c² has three screw-plugs, 21, 22, and 23, to afford access to the bore of said coupling and to the interior of the pipes E' and E², respectively, the injector-casing C being likewise provided with three screw-plugs, 24, 25, and 26—one in the plane of the injector, the other in that of the pipe E², and the third in the transverse axial plane of the casing, respectively, and for like purposes.

The injector C' consists of a tube provided 95 with a nozzle-head, c, that has a small axial gas orifice or passage, c⁵, as shown in Figs. 10 and 11, or with a plurality of such passages grouped around the axis of the nozzle, as shown in Figs. 12 and 13, said tube being 100 screw-threaded for a portion of its length immediately in rear of the nozzle-head for securing it to the injector-casing C. The tube is open at its inner end, and when screwed to the burner said end lodges in a recess, 4^a, 105 formed in the outer end of the screw-plug 24, as shown in Fig. 2, and is closed thereby.

The injector-tube C' may have numerous small peripheral perforations or ports, c⁶, for the passage of the gas or vapor, as shown in Fig. 10, or it may have a few large ports, as shown in Fig. 11, in which case we prefer to introduce into the tube a wire-gauze cylinder, c⁷, to prevent any solid matter from entering the nozzle and obstructing the small outlet 115 orifice or orifices.

When the injector has a plurality of outlet-orifices, the aggregate area thereof will be equal to the area of the single outlet-orifice, as will be readily understood, and this area 120 will vary within certain limits, according to the nature of the illuminant used, and also according to the area of the regenerative pipes, and according to the amount of light the burner is to furnish.

The described construction of injector and casing C C' permits the ready removal and replacing of the injector when necessary from any cause. To more intimately mix air with the escaping jet of vapor or gas, we prefer to employ a combining-cone with the injector C'. This combining-cone D is secured to or formed on the lateral coupling-arm c' of the casing C and depends therefrom im-

mediately in front of the injector C' and concentric therewith. The jet or jets of gas or vapor ejected produce a partial vacuum in the combining-cone D, entraining the ambient air into the cone, wherein it mixes more intimately with the vapor than would be the case were no combining-cone employed. The flame resulting from the combustion of the hydrocarbon gas or vapor in front of the combining-cone D impinges upon the pipes E' E², as stated above, to convert the combustible liquid into a gas and superheat the gas before it reaches the burner for the purposes stated. The illuminating or heating power of the burner may be increased considerably by duplicating the parts thereof, as shown in Figs. 8 and 9, there being two injectors, C' C', two combining-cones, D, and a return heating or regenerative pipe, E³, for the second injector, both injectors being supplied by pipe E. The illuminant from reservoir A passes through pipes E E' to the cross-coupling c², where it divides into two streams and passes to the pipes E² E³, and thence in the form of vapor or gas to the respective injectors, an additional screw-plug, 27, being provided in said cross-coupling c² for pipe E³, as shown, and for the purposes stated.

The burner, as described, is applicable for general indoor use. We have, however, stated hereinbefore that the said burner is more especially designed for use in the open air and on board ships, where it is or may be subjected to the action of strong and shifting air-currents and to more or less vibration.

To protect the burner against the inclemency of the weather, and also to prevent the loss of heat from the flame, and to prevent air-currents from deflecting the flame from the regenerative tubes or pipes, we provide a shield, F, of thin sheet metal, as shown in Figs. 1, 2, 4, 5, and 6, and in dotted lines in Fig. 3. This shield F is preferably hinged at its rear end to bearings c³, formed on the coupling c' of the injector-casing C, and like bearings formed on the shield, by a removable hinge-pintle, c⁹, as shown in Figs. 5 and 6 and in dotted lines in Fig. 4, said shield covering the top of the regenerative pipes and cross-coupling c², its sides projecting downward sufficiently to inclose said pipes. The object of hinging the shield F to the burner by means of a removable hinge-pintle is to adapt the shield to be thrown back off the regenerative pipes, as shown in dotted lines in Fig. 1, or to remove it altogether when not needed. In the arrangement shown the light is thrown downward. The position of the shield may be reversed when the light is to be thrown upward or when the burner is employed as a heater below a surface to be heated where it becomes necessary to throw the heat upwardly. In this case the hinge-pintles are formed on the combining-cone D and suitable means provided to hold the shield in position, or the burner may be reversed. A shield, F', of thin sheet metal, is or may also

be provided for the injector and a combining-cone, as shown in Figs. 1, 5, and 6, and in dotted lines in Figs. 3 and 4, said shield being hinged to the same bearings, c⁸, on the arm c' of the casing C, or to bearings formed on the combining-cone when the position of said shield is to be reversed. The shield F' is closed at its rear end and has a vertical slot, f', for the passage of the pipe E and to admit of its being turned up, and in the top of said shield is formed a hole, f², for the passage of the screw-plug 26 of the casing C, as more plainly shown in Fig. 5. As the shield surrounds the casing, which is heated by the gases or vapors from the regenerative pipes, the air surrounding the burner and drawn into the combining-cone D is also heated, so that the heat radiated from the casing is thus utilized, and air more or less heated is mixed with the gas or vapor, thus promoting the combustion. On the other hand, this shield also protects the flame against sudden gusts of wind. It is obvious that when the shield F is employed the heat around the regenerative pipes is greatly increased, thereby increasing the regenerative power of the burner, and consequently the illuminating-power thereof. The burner being revoluble, it may readily be adjusted to the direction of the air-currents; but when such shift frequently, as is the case when the burner is used on board of a ship, this attention to the burners becomes laborious. To avoid this, we provide the burner with a directing or wind vane, G, as shown in Figs. 1 and 7, the shield being slotted at its outer end, as shown at f, and on the cross-coupling c² is formed a post, g, to which the vane G is secured. The slot f being narrower than the post, the latter serves to hold the shield at a proper elevation above the regenerative pipes. The vane G may be permanently or detachably connected with the post g. In the latter case the stem of the vane fits into a socket in the post and is secured in position by a set-screw, 10, as shown in dotted lines in Fig. 1.

Where the vane is dispensed with altogether, the post g may be secured to the shield F, as shown in Figs. 2 and 5.

By providing the burner with a directing-vane it is at all times held in the direction of air-currents, so that the flame is not deflected from a line or plane parallel with the regenerative pipes or from a line that would impair its illuminating-power.

We have described the shields F and F' as applied to a burner of special construction; but we do not limit ourselves thereto, as said devices may be applied to other styles of burners.

To start the burner, a dish, H, (shown in dotted lines,) may be suspended therefrom and a fibrous material saturated with a hydrocarbon placed in it and ignited to heat the burner sufficiently to generate gas; or the burner may be removed from the supply-pipe B, the shields F F' and vane G detached therefrom, and the burner heated over a fire

sufficiently to generate gas when again connected with the supply-pipe and the supply turned on, after which the said shields and vane may be attached to the burner; or any 5 other mode of heating the burner sufficiently to generate gas may be resorted to.

We do not desire herein to claim, broadly, the combination of an ejector and a mixing or combining cone with a multitubular regenerator the tubes of which are arranged in a projection of the plane of said ejector and combining-cone, as this arrangement is shown in British patent granted to Roughsedge Wallwork, No. 15,328, of November 24, 15 1886, and is also shown, described, and claimed in an application for patent of the United States filed on or about October 23, 1888, Serial No. 289,045.

Having described our invention, what we 20 claim is—

1. The herein-described regenerative burner, comprising an injector and a multitubular regenerator having its tubes connected in series and arranged in a projection of the plane 25 on one side of and in proximity to the injector-nozzle, said injector being connected with the terminal of the multitubular regenerator, substantially as and for the purposes specified.

2. The herein-described regenerative burner, comprising an injector, a combining-cone arranged in front of the injector, and a multitubular regenerator having its tubes connected in series and arranged in a projection of the plane on one side of and in proximity 35 to the injector-nozzle and combining-cone, said injector being connected with the terminal of the multitubular regenerator, substantially as and for the purposes specified.

3. The combination, with a burner for volatile combustible liquids, having its outlet-passage in a horizontal plane, of horizontal regenerative pipes arranged above and extending beyond said outlet-passage, said pipes being connected in series, the initial thereof 40 communicating with a supply-pipe and the terminal with the burner, substantially as and for the purposes specified.

4. The combination, with a burner for volatile combustible liquids, having its outlet-passage in a horizontal plane, and horizontal regenerative pipes arranged above and extending beyond said outlet-passage, of a shield for 45 said pipes, substantially as and for the purposes specified.

5. The combination, with a burner for volatile combustible liquids, having its outlet-passage in a horizontal plane, and horizontal regenerative pipes arranged above and extending beyond said outlet-passage, of a detachable shield for said pipes, substantially as and for the purposes specified.

6. The combination, with a burner for volatile combustible liquids, having its outlet-passage in a horizontal plane, and horizontal regenerative pipes arranged above and extending beyond said outlet-passage, of a detach-

ably-hinged shield for said pipes, substantially as and for the purposes specified.

7. The herein-described burner for volatile combustible liquids, comprising the burner proper, having its outlet-passage in a horizontal plane, and horizontal regenerative pipes arranged above and projecting beyond the outlet-passage, said pipes being connected in series, the initial communicating with the supply of liquid and the terminal with the outlet-passage, a shield for said pipes, and a shield for the burner, substantially as and for the purpose specified.

8. The herein-described burner for volatile combustible liquids, comprising the burner proper, provided with a horizontal discharge-nozzle, a mixing-cone, D, arranged in front of said nozzle, and regenerative pipes arranged above and projecting beyond the nozzle and cone, and a shield inclosing the top and sides of the cone and burner, as well as one end of said burner, substantially as and for the purposes specified.

9. The herein-described burner for volatile combustible liquids, comprising the burner proper, provided with a horizontal discharge-nozzle, a mixing-cone, D, arranged in front of said nozzle, and regenerative pipes arranged above and projecting beyond the nozzle and cone, and a shield hinged to and inclosing the top and sides of the cone and burner, as well as one end of said burner, substantially as and for the purposes specified.

10. The herein-described burner for volatile combustible liquids, comprising the burner proper, provided with a horizontal discharge-nozzle, a mixing-cone, D, arranged in front of said nozzle, and regenerative pipes arranged above and projecting beyond the nozzle and cone, and a detachably-hinged shield inclosing the top and sides of the cone and burner, as well as one end of said burner, substantially as and for the purposes specified.

11. The combination, with a revoluble burner, of a directing-vane to maintain the burner in the direction of air-currents, substantially as described.

12. The combination, with a revoluble burner the tip or nozzle whereof lies in a horizontal plane, of a directing-vane to maintain the burner in the direction of air-currents, substantially as described.

13. The combination, with a revoluble burner the tip or nozzle whereof lies in a horizontal plane, of a horizontal shield arranged above the tip or nozzle and extending beyond the same and a directing-vane, substantially as and for the purposes specified.

14. In an apparatus for illumination with combustible volatile liquids, the combination, with the supply-pipe for the liquid, of a horizontal burner revoluble on said supply-pipe and regenerative pipes connected with the supply-pipe and burner, substantially as and for the purposes specified.

15. In an apparatus for illumination with

combustible volatile liquids, the combination, with the supply-pipe, a horizontal revoluble burner, and regenerative pipes connected with the burner and supply-pipe, of a directing-
5 vane to maintain the burner in the direction of air-currents, substantially as and for the purposes specified.

16. In an apparatus for illumination with combustible volatile liquids, the combination, with the supply-pipe, a horizontal revoluble burner, and horizontal regenerative pipes extending beyond the burner above the plane of the flame and parallel therewith, of a shield arranged above said pipes and a wind-vane
15 at the outer end of the pipes and shield, substantially as and for the purposes specified.

17. In an apparatus for illumination with combustible volatile liquids, the combination, with a forcing apparatus for the combustible liquid and the distributing-pipe of said apparatus, of a horizontal burner revoluble on said distributing-pipe and a wind-vane connected therewith, substantially as and for the purposes specified.

18. In an apparatus for illumination with combustible volatile liquids, the combination, with a forcing apparatus for the combustible liquid and the distributing-pipe of said apparatus, of a horizontal burner revoluble on said pipe, regenerative pipes connected with the burner and distributing-pipe, and a wind-vane to hold the burner in the direction of the wind, substantially as and for the purposes specified.

19. In an apparatus for illumination with combustible volatile liquids, the combination,

with a forcing apparatus for the combustible liquid and the distributing-pipe of said apparatus, of a horizontal burner revoluble on said pipe, regenerative pipes connected with the burner and distributing-pipe and arranged in proximity to the burner-flame, a shield for said pipes and flame, and a wind-vane to hold the burner in the direction of the wind, substantially as and for the purposes specified. 40 45

20. The combination, with the burner C and the nozzle C', constructed substantially as described, of the screw-plug 24, provided with a recess, 4^a, in which the open rear end of the nozzle is seated, substantially as and 50 for the purposes specified.

21. The combination, with the mixing-cone D, of the burner C, the injector-nozzle C', connected therewith and provided with ports c⁶, and the foraminous cylinder c⁷, arranged with- 55 in the nozzle, substantially as and for the purposes specified.

22. The combination, with the burner C, the injector-nozzle C', connected therewith and provided with ports c⁶, and the forami- 60 nous cylinder c⁷, arranged within the nozzle, of the screw-plug 24, provided with a seat, 4^a, for the open end of said nozzle, substantially as and for the purposes specified.

In testimony whereof we affix our signatures 65 in presence of two witnesses.
